UNITED STATES PATENT OFFICE.

JOSEPH G. GAVLAK, OF MONONGAHELA, PENNSYLVANIA.

SPARK PLUG.

Application filed August 10, 1923. Serial No. 656,625.

To all whom it may concern:

Be it known that I, JOSEPH G. GAVLAK, a citizen of the United States, residing at Monongahela, in the county of Washington and State of Pennsylvania, have invented certain new and useful Improvements in Spark Plugs, of which the following is a specification.

This invention relates to spark plugs of the type for use in connection with internal combustion engines, and important objects of the invention are to provide a spark plug having means whereby multiple sparks will be provided for quickly and effectively igniting the explosive charge; which provides a novel and improved device for securing the main insulating core within the metal shell; which permits of the convenient regulation of the spark gap relationship between the various electrodes; which provides for the adjustment of the spark permitting of its efficient use in connection with inferior grades of fuel and which embodies novel means for priming the engine.

It is also within the scope of the invention to provide a spark plug having the improved features above noted, and which at the same time is comparatively simple in its construction and arrangement, durable, compact and inexpensive to manufacture, as well as being thoroughly practical, reliable and efficient in use.

With the foregoing and other objects in view which will appear as the description proceeds the invention resides in the construction, combination and arrangement of parts hereinafter described and illustrated in the accompanying drawing wherein is shown an embodiment of the invention, it being understood that changes in the precise embodiment of the invention herein disclosed, can be made within the scope of what is claimed without departing from the spirit of the invention.

In the drawing forming a portion of this specification and wherein like numerals of reference designate corresponding parts throughout the several views:—

Figure 1 is a side view partially in section of a spark plug constructed in accordance with my invention.

Figure 2 is an enlarged detail side view of the tubular electrode, and Figure 3 is a

perspective view of the annular electrode associated therewith.

Figure 4 is an enlarged section of the priming member.

Figure 5 is a side view of the auxiliary insulating core showing a modified form of electrodes associated therewith.

Referring more particularly to Figure 1, there is shown the main insulating core 1, through which extends the main electrode 2. The main core 1 is secured within a metal casing or shell 3 through the agency of the metal collar 4. The latter is formed with a depending annular flange 5 which is forced into the annular recess 6, formed in the upper portion of the main core 1, during the assembly of the spark plug.

The lower portion of the main core 1 is substantially cone-shaped and is formed with a continuous spiral groove 7, while the upper portion of the core 1 is formed to provide an annular flange 8, for the purposes to be described.

The shell 3 is provided with a horizontally disposed aperture 9, the inner portion of which is reduced and formed to provide a seat which is associated with the corresponding inner end of the bolt 10. The latter threadably engages the enlarged portion of the aperture 9 and is formed with a conduit 10' which terminates at its inner end with a pair of reduced ports 9'. The aperture 9 and associated bolt 10 are provided to permit of the priming of the engine cylinders through the spark plugs. By slightly releasing the bolt 10 in the aperture 9, the priming medium may be injected into the shell 3 through the conduit 10' and ports 9'. The priming medium will enter the spiral groove 7, of the main core 1, and travel therein downwardly toward the lower terminal of the main electrode 2. During such downward travel, the priming medium will vaporize, forming an explosive medium in the vicinity of the spark.

The bolt 10 carries a threadably engaged locking plate 11 for securing the former against rotation in the threaded portion of the aperture 9, when desired.

The shell 3 is provided with the usual peripheral threads 12 for attaching the plug into the engine cylinder. The lower face shell shoulder is formed with a plurality of

annular grooves, providing annular projections 13 therebetween which are adapted to engage the cylinder head, or preferably the washers 14 if used between the cylinder head and the shell shoulder, for establishing a perfectly tight connection.

The shell 3 is provided with a contracted lower end 15, the inner wall of which is threaded. Threadably mounted in the 10 threaded lower end 15, of the shell 3, is a bushing 16 in which an auxiliary core 17 is fixedly supported. The core 17 is formed with a threaded central bore in which a tubular electrode 18 is threadably mounted. 15 The upper end of the tubular electrode 18 is aligned and coacts with the lower end of the electrode 2 and is provided with a plurality of vertically disposed slots 19 open at their upper ends. The lower end is also 20 provided with a plurality of open slots 20, and is flared, as indicated at 21. The slots 19 and 20 are provided to prevent deterioration of the functioning ends of the tubular electrode 18 by establishing a plurality of 25 firing ends which will not become inactive at the same time by pitting or other causes.

An inner annular electrode 22 surrounds the lower end of the tubular electrode 18 and is supported from the lower end of the 30 metal shell 3. The annular electrode 22 forms a spark gap at any point from the tubular electrode 18.

The lower portion of the shell 3 is provided with a plurality of large openings 23 35 to allow the escape of the spark, formed between the adjacent ends of the electrodes 2 and 18, to the explosion chamber of the engine cylinder. The tubular electrode 18 with its flared lower end 21 also serves to facilitate the escape of the spark therethrough to the explosion chamber, and for this reason the passage opening through the tubular electrode 18 is preferably tapered as clearly shown in Figure 2, of the 40 drawing.

A metal cap 24 is fixed to the upper end 45 of the main core 1 by the engagement of its lower edge with the annular flange 8. A terminal binding post 25 is mounted on top of the cap 24. A pair of adjustable spark regulating screws 26 and 27 are threadably mounted in the cap 24. The screws 26 and 50 27 are preferably diametrically disposed relatively to each other, but not essentially so. A pair of openings 28 are formed in the cap 24 and are disposed at right angles with respect to the screws 26 and 27, and are diametrically disposed with respect to each other.

60 A metal cap nut threadably engages the upper end of the main electrode 2 and coacts with the spark adjusting screws 26 and 27.

65 The screw 26 is comparatively light and is adapted to be adjusted to coact with the

nut 28 to produce a light or lean spark for use in connection with high grade light fuel, while the screw 27 is heavy and adapted to coact with the cap nut 28 to produce a fat spark adaptable for use in connection with 70 inferior heavy grades of fuel. The openings 28, are formed in the cap 24, permit of the spark being seen when either of the screws 26 or 27 are being adjusted to the position required, or to ascertain whether the spark 75 plug is functioning properly.

It will be noted that the construction of my improved spark plug will not only allow the regulation of the spark by the ready adjustment of the screws 26 and 27 as above 80 described, but will permit also of the adjustment of the tubular electrode 18 in the auxiliary core 17, and the adjustment of the bushing 16 in the shell 3.

The modification illustrated in Figure 5, 85 of the drawing, comprises an auxiliary insulating core 29 adapted to be mounted in the bushing 16, of the preferred form, instead of the core 17 and associated parts as described relative to the preferred form. 90 The core 29 is provided with a central electrode 30 and a pair of secondary electrodes 31 and 32. The electrode 31 coacts with the electrode 30 and the electrode 32 coacts with the electrode 31 whereby a plurality of 95 sparks are provided.

What I claim is:—

1. A spark plug comprising a main electrode, a peripherally threaded tubular electrode co-acting with, spaced from and arranged in lengthwise alignment with respect to the main electrode, an inner electrode associating with said tubular electrode, a pair of spaced cores of insulation, one of said cores carrying the main electrode and the outer of said cores having a threaded core through which extends the tubular electrode, the latter having threaded engagement with the wall of the bore, a metallic shell supporting the core carrying the main electrode 100 and carrying said inner electrode, and a bushing secured in the inner end of said shell and supporting said threaded core.

2. A spark plug comprising a main electrode, a peripherally threaded tubular electrode co-acting with, spaced from and arranged in length-wise alignment with respect to the main electrode, an inner electrode associating with said tubular electrode, a pair of spaced cores of insulation, one of 115 said cores carrying the main electrode and the other of said cores having a threaded bore through which extends the tubular electrode, the latter having threaded engagement with the wall of the bore, and means for supporting said cores and carrying said inner electrode, and said tubular electrode 120 provided with slotted flaring ends.

3. A spark plug comprising a main electrode, a peripherally threaded tubular elec- 130

- trode co-acting with, spaced from and arranged in length-wise alignment with respect to the main electrode, an inner electrode associated with said tubular electrode, 5 a pair of spaced cores of insulation, one of said cores carrying the main electrode and the outer of said cores having a threaded bore through which extends the tubular electrode the latter having threaded engagement 10 with the wall of the bore, a metallic shell supporting the core carrying the main electrode and carrying said inner electrode, and a bushing secured in the inner end of said shell and supporting said threaded core, and 15 said tubular electrode extending above and below said bushing and formed with slotted flaring ends.
4. A plug comprising a metallic shell, a core of insulation clamped to and depending 20 therein, a central electrode extended through said core, said shell having a contracted inner end, a bushing secured to and projecting from said inner end, a tubular electrode aligning and co-acting with and spaced from
- said central electrode, a core of insulation 25 carried by said bushing and having the central electrode extended therethrough, and threadably engaging therewith, and an inner electrode projected inwardly from said shell and co-acting with the tubular electrode. 30
5. A plug comprising a metallic shell, a core of insulation clamped to and depending 35 therein, a central electrode extended through said core, said shell having a contracted inner end, a bushing secured to and projecting from said inner end, a tubular electrode aligning and co-acting with and spaced from said central electrode, a core of insulation carried by said bushing and having the central electrode extended therethrough, and 40 threadably engaging therewith, an inner electrode projected inwardly from said shell and co-acting with the tubular electrode, said tubular electrode having flaring slotted end portions.

In testimony whereof I affix my signature.

JOSEPH G. GAVLAK.
